UNITED STATES PATENT OFFICE.

CORRADO ANDREINI, OF GROSSETO, ITALY.

PUMP OF VARIABLE RESISTANCE.

Application filed July 1, 1922. Serial No. 572,162.

To all whom it may concern:

Be it known that I, CORRADO ANDREINI, a subject of the King of Italy, and residing at Grosseto, Italy, have invented certain new and useful Improvements in Pumps of Variable Resistance, of which the following is a specification.

In the usual types of pumps the operation is constant if the speed of the pistons and the lift are constant. Consequently the latter require a constant driving power.

The object of this invention is to provide a pump in which a variable operation is effected by keeping the lift constant so that if the motor employed is of a variable power it is possible to utilize all the available power from a minimum to a predetermined maximum under the only condition that in correspondence of the variations of H. P. variations of the velocity of the motor must take place within limited range.

The invention is especially useful on wind motors when used.

The invention is clearly illustrated in the accompanying drawings, in which:—

Fig. 1 is a vertical longitudinal section of the pump,

Fig. 2 is a vertical cross section thereof,

Fig. 3 is a horizontal section on the line 3—3 of Fig. 2,

Figs. 4 and 5 are enlarged elevational and section details respectively, and

Figs. 6 and 7 are enlarged elevational details partly in section of the equilibrated valve in different positions.

Referring now, more particularly, to the accompanying drawings there is provided a suction and force pump with two identical cylinders and pistons having at every instant an equal movement in opposite directions, that is, when one moves upwardly the other moves downwardly at equal speed so that the volumes created by the movements thereof are always the same. The adoption of two cylinders instead of one has permitted besides the compensation of the volumes a smaller section of the pistons, equal disposition of the strain and the use of small air chambers. The pump consists of a carter 1 preferably of cast iron having in the lower part thereof two cylinders 2 in which the pistons 3 operate. The pistons are actu-

ated by the connecting rods 4 which in turn are coupled to the oscillating beam 5 mounted on an axle 6. The cylinders are joined together adjacent the front face thereof by a wall 7 and are likewise joined adjacent the rear face by another wall 8 being also connected at the medial portions thereof by a diaphragm 9 so that between the cylinders 55 the walls 7 and 8 and the diaphragm 9 two separate chambers 10 and 11 are provided. The chamber 10 communicates with the chamber 11 through the porthole 13 and passageway 48 as well as the valve 14 while 60 the chamber 11 communicates with the chamber 12 in the base of the carter through portholes 14' and valve 22' and with the upper part of the carter through the equilibrated valve 15. By means of this arrangement the operation of the suction air chamber 11 is permitted even when the equilibrated valve 15 is open while the operation 65 of the pump can even take place in the case of a very high lift.

The carter 1 is closed by the cover 16 through which the axle 6 passes. A stuffing box gland 17 prevents escape between the axle 6 and the cover 16. The chamber 10 is also provided with a flanged opened end 18 in which is inserted suction pipe 19 of the pump while the chamber 11 is provided with a hole through which the equilibrated valve 15 is arranged. The carter is provided at its upper portion with a flange 20 for the 70 air chamber 21. The axle 6 is fitted with one of its ends into a support 22 preferably of bronze and fixed in turn on the carter by suitable fastening such as bolts.

It is preferred that the cylinders be 75 formed of cast iron and integral with the carter and coated with bronze to prevent the formation of rust. It may also be noted that the suction valves 22' are provided with small guide rings and cones to facilitate the flowing of water.

The pistons are fitted with a double leather packing 23 and with valves similar to the valves 22' and interchangeable with the same. The connecting rods are forked 80 at opposite ends and are clamped by means of bolts 24 to the ends of the rocking beam 5 and the piston 3. The rocking beam 5 is fixed in turn on the axle 6 by a wedge which 100

is provided with an annular segment 25 while the axle 6 formed preferably of homogeneous iron case on its outer part forms a prolongation in the form of a pyramid 5 trunk with a threaded stalk for the external beam coupling. The equilibrated valve 15 is formed with a movable cover 26 carrying the roll 27 and three small wings 28. The cover is slidable in the cylinder while 10 the bottom bears on the seats 30 and 31 of the double seated tubular valve 32. A slightly conical spring 23 serves to maintain the valve support on the seats. The tubular valve is provided with three pivots 15 34 bearing on the under lip of the cover so as to slide along three generators of the cylinder 29 in which three portholes 35 are arranged. The double seated valve is equilibrated with respect to the pressure in the 20 carter as the two circular crowns are equal while it is not so with the depressions taking place in the chamber 11.

The stroke moderator mechanism is composed of a perforated cylinder 36 preferably of brass in which operates a piston 37 carrying an elastic ring 38.

The cylinder is pivoted to a connecting rod which in turn oscillates about an arm 40. The oscillating arm carries an arcuate 30 flanged arm the outer end of which supports a roll 42. The arm 41 rests on the friction roll 27 while the other roll 42 is arranged in contact with the bearing of the rocking arm 40. A strainer 43 preferably 35 of thick brass prevents foreign matter from entering the chamber 10.

The operation of the pump is as follows:—

By causing the axle 6 to oscillate the pistons move alternatively and the water is 40 drawn up by the lower faces thereof and forced by the upper faces into the carter as in all lift and force pumps through the same play of valves. Therefore in chamber 45 10 there is provided a depression (never higher than $\frac{8}{10}$ of atmosphere) while in the carter a compression is provided which is increased at an extent sufficient to overcome the elevation which can reach about 12 atmospheres. This remains until the equilibrated valve is seated.

Assuming now that at a set point of the upper stroke of the right hand piston the equilibrated valve 15 opens. In this case 55 the carter 1 is arranged in communication with the chamber 11 and the pressures in the two chambers will equal each other while the difference of pressure between chambers 10 and 11 will cause the valve 14 to fall on 60 its seat thus cutting off communication between the chambers 10 and 11 so that while in chamber 11 a pressure takes place in the chamber 10 there is still a depression which allows the water of the suction column to 65 keep in motion. The upper face of the pis-

on drives the above mentioned standing water into the carter whence through the equilibrated valve 15 it flows to chamber 11 and through the portholes 14' into chamber 12 and from this latter chamber through 70 the suction valve 22' so as to fill the chamber created in the same cylinder by the movement of the suction head. In such a case therefore the operation of the pump is reduced to a mere passive resistance. 75

The opening of the equilibrated valve 15 is determined by the annular segment 25 which upon meeting the roll 42 forces the arm 41 to press upon the roll 27 and in consequence to open the equilibrated valve 15 by means of the pivots 34. If the arm 40 turns about the bearing 21 according to the position it takes, the annular segment 25 will meet the roller 42 sooner or later and will therefore open the equilibrated valve 85 at different points of the stroke of the plunger. The displacement of the oscillating arm 40 is brought about by the movement of the piston 37 through the connecting rod 39. When the piston 37 has reached its uppermost position, the segment 25 no longer meets the roll 42 and the pump will work at full load like the common suction and force pump.

In the operation of the stroke regulator 95 as the speed of rotation of the fly wheel is proportionate to the velocity of the wind, the delivery of a pump driven by a wind motor will also be proportionate to the velocity of the wind. Supposing therefore 100 that to the lowest possible movement the piston 37 should correspond such as an inner angle of the arm, that the equilibrated valve 15 will open for instance after a 4 cm. stroke of the right hand position, it 105 will remain open for the remainder of the stroke of this position and for that of the left hand position as far as about 4 cm. of the end of the stroke. In other words, the pump will have the same delivery of the 110 usual type of pump with two cylinders of equal diameter and 4 cm. stroke. Assuming that piston 37 slides without friction in the pipe 36 and at the same time keeps a perfect tightness along the walls if P represents the weight of the piston and connecting rod immersed in the water (the weight of the rocking arm is not considered) and the area of its lower face expressed in cm., and assuming that in this position the piston leaves a hole drilled in the wall of the pipe 36 of area A uncovered, from the formulas relating to the outlets and striking against the thin walls it results that the water passing through the hole in the unit 115 of time will be

$$q = nA\sqrt{2gh}$$

where n and g are two constants and h represents the difference between the load in 120 125

the carter and that of the forcing column in order that the flowing through hole A with a delivery q may take place out of the foregoing formula it results that:

$$5 \quad h = \frac{q^2}{n^2 A^2 2g}$$

from which it is deduced, $n_2 A_2 2g$ being a constant valve and by putting:

$$10 \quad \frac{1}{n^2 A^2 2g} = c$$

and then the result $h = cg^2$.

The load required to produce the variable 15 delivery q through the hole of the section A varies in direct proportion to the delivery square. This load that is in the carter and that of the forcing column and of the air chamber 21 is expressed in m. of water.

20 By reducing to kg. each cm² (calling p the unit pressure) it results that

$$H \\ p = \frac{10.33}{}$$

25 or in other words

$$p = \frac{cg^2}{10.33}$$

This difference of pression bears on every 30 surface unit of the lower face of the piston 37 and therefore a being the area of the said face there will be a power upon it of:

$$ap = a \frac{cg^2}{10.33}$$

35 that tries to cause a slight movement of the piston itself, but the piston will remain in the initial position until

40 $P < ap$ that is P (weight of the piston) = $\frac{acg^2}{10.33}$

However along with the increase of the velocity of the wind and in consequence of q , p rises in direct proportion so that after 45 a certain time p will be greater than P_a . In this event the piston 37 will be shifted upwardly. By this movement it uncovers another hole or opening and at the same time it varies the inner angle of the rocking 50 arm and lengthens the useful stroke of the piston to which a greater L_r corresponds. In this new position either the whole delivery will pass under pression p through the section of the uncovered holes so that the 55 equation

$$p = \frac{cg^2}{10.33} = \frac{P}{a}$$

60 will take place; or a new pression will ensue causing another upward stroke of the piston and thus the uncovering of the new holes and the increase of delivery etc. until the speed of the motor and delivery of the 65 pump are unbalanced so that the whole of

this may pass through the uncovered holes so that the pression will equal $\frac{P}{a}$ or that

work L_r results greater than L_m . In this 70 case the number of revolutions of the motor will be reduced thereby causing the diminution of the delivery and in consequence a pistons possible descent and a diminution in the useful stroke until equilibrium has 75 been established. In calculating the section of the holes it being settled that the delivery of the pump shall be such as to absorb the different velocities of the wind, the whole 80 motor power, the equilibrium will only be obtained when L_m is equal to L_r . In the above stated description it has been admitted that the minimum useful stroke of the piston should be 4 cm. (which effectively 85 in the pump under consideration operated by the wind will at centrifugal force with a wheel of m. 1.60 diameter and 25 in elevation corresponds to a 3 m. wind), but to make sure that the equation $L_m = L_r$ should take place from the initial movement up to 90 the time when the pump operates at full load then the following will occur. Having fixed the velocity of the wind at which the wind motor starts there is next fixed the available power the number of revolutions 95 of the fly wheel, and in consequence the pistons average speed with such velocity of wind.

Then the total upper elevation being given it follows that by putting the condition that 100 the motor work should equal the resisting one and by fixing the theoretic delivery that the pump must have in order to absorb the whole power of the motor and the delivery the pump would have at the same speed for 105 the whole stroke of the pistons.

This being stated from the proportion interceding between strokes and deliveries it is easy to deduce the length of the useful 110 stroke so that the equation $L_m = L_r$ should take place and then determine the inner angle of the oscillating arm which is given by the useful stroke as determined above. As the weight in the water of the piston and connecting rod is known there is next 115 fixed the area of the hole through which the water passes by velocity of the wind and by repeating the calculations for the velocity of the other winds, there is thus determined the sections of the holes in the various positions of the piston 37.

Having attained the maximum stroke the annular segment 25 does not have to meet the roller 42 to cause the movement of the hand and the raising of the valve 15. As 125 a result the pump operates as an ordinary pump and the delivery thereof increases with the speed of rotation of the fly wheel but the latter cannot exceed an absolute maximum on account of the centrifugal 130

- force regulator of the motor. At this limit speed all the uncovered holes will leave free passage to the whole delivery under a fixed weight or load. The valve 15 being equilibrated through the pressures existing in the carter does not hinder in any way the opening but the spring will have to ensure the perfect tightness under the sucking action that attempts to raise it from the seat.
- 10 There is never any great amount of strain. The water having passed through the holes 36 in the cylinder flows into the air chamber 21 and thence up the ascending column 44 either directly or through a reducing valve 15 45 if the upper elevation is strong.

In the case of very high lifts, in the lower portion of the right hand cylinder, that is, the one on the side of the air chamber, there is provided a pipe which communicates with 20 a small valve that opens automatically by means of a contrivance like that described for the intermittent action of the oil pump for a short while each 990 double movements of the beam and it serves to restore 25 the air into the air chamber, air which under strong pressure has been dissolving in the water.

As the drawing shows the communicating tube between the carter and the chamber 11 30 the continuation of the equilibrated valve is very short and the section thereof as well as the sections of passage through the valve and the portholes of communication between the chambers 11 and 12 are such as to cause 35 no material loss of load during the time the pump is idle.

The suction air chamber besides avoiding water strokes during the opening of the equilibrated valve, prevents the freezing of 40 water from injuring the pump which latter being siphon shaped is always primed independently of the suction and foot valves.

Having thus fully described the invention what is claimed as new and desired to be 45 secured by Letters Patent is:—

1. A variable resistance reciprocating pump having a pressure and a suction side; an equilibrated valve controlling a passage between the two sides of the pump; a spring 50 normally holding the valve closed; valve operating means moving in synchronism with the pump; adjustable means forming an operating connection between the valve and the operating means; and means gov-

erned by the pressure at the pressure side of 55 the pump for positioning the variable intermediary means to cause the said valve to be opened earlier or later as the pressure falls or rises.

2. A variable resistance reciprocating 60 pump constructed as set forth in claim 1 in which the suction side of the pump comprises an inlet chamber; an intermediate chamber and passage connecting the two; and check valve preventing backflow from 65 the intermediate chamber to the inlet chamber; and a passage forming a communication between the intermediate chamber and the suction ends of the pump cylinders.

3. A variable resistance reciprocating 70 pump constructed as set forth in claim 1 in which the operating connection between the equilibrated valve and the operating means comprises a member movable by the governing 75 means to different position to be contacted by the operating means at different parts of the pump's cycle of operation.

4. A variable resistance reciprocating 80 pump constructed as set forth in claim 1 in which the governing means comprises a discharge conduit; a cylinder having one end open to the pressure side of the pump and extending into the conduit and having openings 85 in its wall at different points longitudinally thereof leading to the conduit; and a piston movable to uncover said holes.

5. A variable resistance reciprocating 90 pump constructed as set forth in claim 1 in which the operating connection between the equilibrated valve and the operating means 95 comprises a member movable by the governing means to different positions to be contacted by the operating means at different parts of the pump's cycle of operation; and the governing means comprises a discharge conduit; a cylinder having one end open to the pressure side of the pump and extending into the conduit and having openings in its wall at different points longitudinally thereof leading to the conduit; and a piston movable to uncover said holes.

In testimony whereof I have hereunto signed my name in the presence of two witnesses:

CORRADO ANDREINI.
